(57) **CLAIM**

The ornamental design for a soundproofing cover for engine generator, as shown and described.

DESCRIPTION

FIG. 1 is a perspective view of a soundproofing cover for engine generator showing our new design

FIG. 2 is a second perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a left side elevation view thereof.

FIG. 8 is a right side elevation view thereof; and,

FIG. 9 is a third perspective view thereof, shown in use.

The matter shown in broken lines is for illustrative purposes and forms

The portion of the article shown in broken lines is for illustrative purpose only and forms no part of the claimed design. no part of the claimed design.
